UNITED STATES PATENT OFFICE.

CHARLES H. HALT, OF NEW HAVEN, INDIANA, ASSIGNOR TO NON-EXPLOSIVE APPLIANCE COMPANY, OF FORT WAYNE, INDIANA, A CORPORATION.

OIL-STOVE.

1,364,631.

Specification of Letters Patent.

Patented Jan. 4, 1921.

Application filed August 2, 1919. Serial No. 314,811.

To all whom it may concern:

Be it known that I, CHARLES H. HALT, a citizen of the United States, and a resident of New Haven, county of Allen, and State 5 of Indiana, have invented certain new and useful Oil-Stoves; and I do hereby declare that the following is a full, clear, and exact description thereof, reference being had to the accompanying drawings, in which like 10 numerals refer to like parts.

The object of this invention is to improve the safety and the operation of gasoline stoves.

One feature of the invention consists in 15 a construction of the gasoline tank and supply pipe to the burners so that the gasoline tank can be filled while the stove is burning without any danger.

Another feature of the invention consists 20 in providing beneath each burner a receptacle for catching the gasoline which overflows from a burner while the fire is being started and conveying the overflowed gasoline away to a tank from which it can be 25 removed and afterward used.

The full nature of this invention will be understood from the accompanying drawing and the following description and claims.

30 The drawing shows a front elevation of the stove, with a part broken away and a part in dotted lines.

There is shown herein a gasoline stove 10 with burners 11, supply pipe 12 and a 35 tank 13. A tube 14 leads from the supply pipe 12 up to each burner. There is a shut off valve 15 and a regulating valve 115 in said tube between the supply pipe and the burner. With this construction the gasoline 40 always stands in the tubes 14 as high as the valve 15, and, therefore, constitutes a liquid seal between the burners and the tank 13 which prevents the possibility of gas accumulating in the pipe or tank, whereby an 45 explosion might arise.

The tank 13 has a goose neck inlet 17 for filling the same. As shown, it extends downward and then upward with the upper discharge end below the inlet end and the top 50 of the tank. Gasoline always stands in pipe 17, as shown, and constitutes a liquid seal. There is in the top of the tank an air vent which consists of a raised cap member 25 which incloses and tightly clamps a cork 55 insert 26. The cap 25 is provided with pin

holes but there is no special opening through the cork. Air may be drawn in through the pin holes and filtered through the cork to fill the space in the tank not occupied by the gasoline, as the gasoline lowers therein, 60 and also cap 25 will relieve the tank of any excess air or gas pressure therein. The pipe 17 is closed by a removable screw cap or the like 27.

Under each burner a funnel 20 is mounted 65 so as to receive all the overflow gasoline coming from said burners which may not be consumed and the gasoline received by the funnel 20 passes through a short tube 21 into a drain pipe 22 that discharges 70 into a drain tank 23. The gasoline can be removed from that tank and put into tank 13 when desired.

The tank 23 has an air vent in the top thereof closed by a perforated cap 28 with a cork 75 insert therein the same as is provided for the tank 13 and for the same purpose, namely, to permit the passage of air or gas and prevent any opportunity for fire or flame to enter the tank and cause an explosion. 80

In starting this gasoline stove, shut off valve 15 and regulating valve 115 are opened and, as the gasoline issues at the burner, it is lighted with a match and left 85 to burn. If there be any overflow gasoline, it will be received by the funnel 20 and conveyed to the tank 23. When the burner becomes heated the overflow will cease.

With this construction of gasoline stove 90 the fuel tank can be filled while the stove is in use by reason of having the peculiar inlet 17 and the air vent closure in combination with the pipes 12 and 14, whereby the gasoline will stand in said pipes up to valve 15. 95 After the match is touched to the gasoline for starting, no further attention need be given for the purpose of starting the fire. This makes the stove safe and removes the cause of explosions, conflagrations and personal injuries. 100

The invention claimed is:

1. A gasoline stove including a burner, a gasoline supply tank, a supply pipe leading from said tank and extending horizontally below the burner, a tube leading from said pipe upward to the burner, a regulating valve in said tube, a shut off valve in said tube below the regulating valve, an inlet tube through which the gasoline tank 110

is filled which is formed so as always to retain sufficient gasoline to seal it and a protected air vent in the upper part of the tank.

2. A gasoline stove including a burner, 5 means for supplying gasoline to the burner, a receptacle below said burner for receiving the overflow of gasoline therefrom, a tank

into which the gasoline drains from said receptacle, and an air vent in the top of said tank consisting of a perforated cap 10 with a cork insert.

In witness whereof, I have hereunto affixed my signature.

CHARLES H. HALT.
